CLAIM

The ornamental design for display screen with epioscopy icon, as shown and described.

DESCRIPTION

FIG. 1 is a front view of a display screen with epioscopy icon showing the new design; and,

FIG. 2 is an enlarged view of the display screen with epioscopy icon of FIG. 1.

The outermost broken line rectangle illustrates a display screen and forms no part of the claimed design. The remaining broken lines illustrate portions of the graphical user interface that form no part of the claimed design. The long-dash/short-dash line illustrates the boundary of the enlarged drawing view and forms no part of the claim.
